UNITED STATES PATENT OFFICE.

LLOYD E. ASHE, OF VASSAR, MICHIGAN.

DITCHING-MACHINE.

1,100,414.

Specification of Letters Patent. Patented June 16, 1914.

Application filed July 19, 1912. Serial No. 710,483.

To all whom it may concern:

Be it known that I, LLOYD E. ASHE, a citizen of the United States, residing at Vassar, in the county of Tuscola, State of Michigan,

5 have invented certain new and useful Improvements in Ditching-Machines; and I do hereby declare the following to be a full, clear, and exact description of the invention, such as will enable others skilled in 10 the art to which it appertains to make and use the same.

This invention relates to new and useful improvements in ditching machines and the purpose thereof consists in the provision of 15 a simple machine of this character for cutting ditches or drains in an expeditious manner and for removing the dirt and discharging the same at opposite sides of the ditch.

20 The primary purpose of the invention consists in providing a machine which is devoid of the usual cumbersome and intricate working parts usually found in machines of this character, whereby the draft is considerably decreased so as to permit a 25 more economical use of the machine as well as decreasing the possibility of the device getting out of working order.

Another essential object of the invention 30 is to provide a ditching machine having an excavating point carried by a wheeled frame and adapted to discharge on to an endless elevator for conveying the excavated material to the rear end of the machine where 35 the same is discharged on to a chute for depositing the same at opposite sides of the ditch while means are also provided for raising and lowering the point and forward end of the elevator to regulate the depth of 40 the ditch cut.

Another and important object of the invention consists in providing novel means carried at the rear end of the machine for vertical adjustment and adapted to operate 45 on the ground surface to loosen the soil in the rear of the ditch during the advancement of the machine whereby the ditching operation is greatly facilitated and the hard surface soil much more easily penetrated.

50 With these and other objects in view, the invention consists of certain other combi-

nations and arrangements of parts as will be hereinafter more fully described, claimed and illustrated in the accompanying drawings, in which:

55

Figure 1 is a side elevation of my improved ditching machine in use but with the nearest longitudinal beam removed, Fig. 2 is a plan view of the machine, Fig. 3 is a longitudinal sectional view of the machine, 60 Fig. 4 is a rear elevation of the machine, Fig. 5 is a cross sectional view taken on the line 5—5 of Fig. 2, and Fig. 6 is a sectional view taken on the line 6—6 of Fig. 2.

The ditching machine comprises two main 65 longitudinal beams 10 the same being suitably supported at their forward ends by traction wheels 11 rotatably mounted upon the journal ends of a front axle 12 from which the forward portions of the beams 10 70 are suspended rigidly as shown. The beams 10 are also similarly supported beneath the rear axle 13 rearwardly of which they extend, the said rear axle 13 having traction wheels 14 journaled on its ends and the 75 beams 10 are mounted on the axles 12 and 13 on each side of the longitudinal centers of the axles for the accommodation of the ditching apparatus which will be herein-after more fully described. Rigidly secured 80 to and projecting forwardly of the axle 12 is a draft tongue 15 which is provided with a four-horse plow 16 for the attachment of four draft animals in advancing the machine.

85

An elevator frame 17 is disposed in an inclined position between the beams 10 and is pivotally supported on the latter near its rear end and forwardly of the axle 13 by means of a plate 18 which is secured to the 90 upper faces of the beams and provided with spaced upwardly extending apertured bearings 19 while the elevator frame carries a plate 20 having depending apertured bearing members 21 pivotally secured between 95 the bearing members 19 by a pin 22 so as to allow pivotal movement of the forward end of the elevator frame toward and away from the ground surface.

Rotatably mounted or journaled in the 100 forward and rear ends of the elevator frame 17 and between the sides thereof, are rollers

23 and 24 which have an endless elevator or conveyer 25 engaged therearound and operating over an intermediate apron 26 connecting the side portions of the elevator frame, 5 and the endless band forming the elevator or conveyer carries transversely disposed and equi-distantly spaced scoops or buckets 27 for receiving and conveying the excavated material from the forward end of the machine or elevator to the rear end thereof.

An elevator point 28 is secured to the forward end of the elevator frame 17 and is adapted to be projected into the ground surface in the manner of a plow to hoist or 15 discharge the dirt on to the elevator to be conveyed upwardly and rearwardly by the scoops or buckets 27.

Keyed to the shafts of the rollers 23 and 24 toward the inside of the elevator frame 20 17 are sprocket wheels 29 and 30 respectively, around which endless drive chains 31 operate and are continuously driven during the advancement of the machine by engagement of one chain with a sprocket wheel 31' 25 driven by a pinion 32 carried by the adjacent rear traction wheel 14 and a gear wheel 33, rotatably supported upon the adjacent end of the axle 13 upon a bearing 34 and disposed in mesh with the sprocket wheel 32 at 30 all times, so as to continuously operate the elevator by engagement with the lower lap of the endless drive chain engaged with said sprocket wheel. A bracket 35 is secured to the upper faces of the rear end of the beams 35 10 and projects rearwardly thereof for supporting a chute having oppositely inclined side portions 36 extending beyond the sides of the beams whereby as the elevated dirt or material is discharged from the scoops or 40 buckets 27 at the rear end of the conveyer, such dirt and material will fall on to the apex portion of the chute and be discharged by gravity down the inclined side portions to the opposite sides of the machine. It is of 45 course understood that one side of the chute may be removed or obstructed in order to discharge the materials at one side of the machine only.

In order to raise or lower the excavating 50 point 28 at the forward end of the elevator, according to the desired depth of the ditch to be cut or the condition of the ground surface, that is when hard or soft, I provide a pair of vertical rack bars 37 having teeth 38 on their rear faces and upper portions while their lower ends operate through pairs of guides 39 projecting from one side of each beam 10 while the lower ends of the rack bars are connected to the elevator frame near 55 its forward end by an arch as shown at 40. Large hand wheels 41 are rotatably mounted on upright bearings 42 carried upon the beams 10 and are provided with pinions 43 normally in mesh with the teeth of the rack

bars and adapted to be manually rotated 65 through the medium of radial hand grips or arms 44 carried by the hand wheels 41 so as to move the rack bars vertically and correspondingly raise or lower the excavator point. During this adjustment, the elevator 70 frame 17 will pivot upon the pin 22 and since the portion of the elevator frame disposed forwardly of the pivot is greatly increased in length relative to the portion projecting rearwardly of said pivot, the rear 75 end of the elevator frame will have comparatively little movement with respect to the forward end thereof and will not interfere with the proper discharge of the dirt or materials on to the chute.

80 A soil loosening or scraping device 45 is mounted between the rear ends of the beams 10 and between the rear wheels 14 so as to operate in the rear of the excavating point and elevator which device comprises in general, a frame portion from which the points 46 depend, as well as cultivator disks 47 and the forward end of the frame is pivotally connected to the beams 10 forwardly thereof by link rods 48. This soil loosening or 85 scraping device is capable of adjustment toward and away from the ground surface through the medium of a pair of vertically extending operating screws 49 preferably engaged through bracket sleeves 50 secured 90 between the beams 10 while the lower ends of the screws are swiveled to brackets 51 secured to the upper face of the frame forming the soil loosening or scraping device 45 and are capable of manual operation by 95 means of hand wheels 52 carried at the upper ends of the operating screws.

100 In the operation of the machine, with the draft animals attached to the evener 16 the plow point and scraping device are held in a 105 raised position and the machine drawn to the desired point upon the traction wheels 11 and 14. The point is then lowered through the medium of the operating wheels 41 to engage the ground surface whereby during 110 the advancement of the machine, the point will elevate the surface dirt which is loose and the scraping device is then lowered for operation beneath the machine and the dirt directly behind and in rear thereof is loosened whereby the next operation of the point will increase the depth of the ditch and the operation is to be continued until the required depth is obtained.

115 It will thus be evident that a machine constructed in accordance with the foregoing description and as illustrated in the accompanying drawings, will be void of all intricate working parts generally employed in devices of this character and it will be further seen that since the draft of the machine is correspondingly decreased, the full benefit 120 is derived from the weight of the machine.

for permitting the point of the elevator to operate at a much increased depth and thereby more expeditiously complete the drains.

I claim:

- 5 The combination with a wheeled frame including spaced side members, of an elevator pivotally supported upon said frame, an excavating point at the forward end of the elevator, vertically adjustable lead screws
- 10 mounted on the frame at the rear of the excavating point, a second frame supported by

the lead screws at the lower ends of the latter, and plow elements carried by the second frame for loosening the soil to a greater depth than the excavating point.

In testimony whereof, I affix my signature, in presence of two witnesses.

LLOYD E. ASHE.
